UNITED STATES PATENT OFFICE

96,427

DESIGN FOR A SHOE

Otto F. Stock, Columbus, Ohio, assignor to The Julian & Kokenge Company, Columbus, Ohio, a corporation of Ohio

Application May 16, 1935, Serial No. 56,870

Term of patent 3½ years

To all whom it may concern:

Be it known that I, Otto F. Stock, a citizen of the United States, residing at Columbus, in the county of Franklin and State of Ohio, have invented a new, original, and ornamental Design for Shoe, of which the following is a specification, reference being had to the accompanying drawing, forming a part thereof.

I claim:
The ornamental design for a shoe, as shown.

OTTO F. STOCK.
